BURIAL APPARATUS

Benjamin F. Austin, East Gastonia, N. C.

Application February 26, 1937, Serial No. 127,976

1 Claim. (Cl. 27—32)

This invention relates to a burial apparatus for use in lowering caskets into a grave and more especially to one which comprises a carriage so constructed that it will travel upon a suitable trackway arranged near the grave.

It is therefore an object of this invention to provide an apparatus of the class described which may be used for lowering the casket into the grave in a dignified and solemn manner in keeping with the nature of the ceremony, without the necessity of the pall-bearers approaching too close to the edge of the grave and running the risk of the edge thereof caving in. In order to eliminate this danger it is necessary to provide a trackway leading up to the grave and a carriage for travelling on said trackway which can be used for placing the casket thereon. Of course the casket will be placed upon the carriage when the carriage is positioned on the trackway at a point removed from the lowering position. This will eliminate the necessity of the pall-bearers approaching the edges of the grave. Also by providing a carriage for transporting or conveying the casket over the grave, it will prevent the walking on the artificial grass which is usually placed around the grave as an ornament. Furthermore it will make it unnecessary for any one to pass between the bereaved family and the casket prior to the lowering of the casket into the grave.

It is a further object of this invention to provide a burial apparatus comprising a trackway extending longitudinally on each side of the grave and for some distance from one end of the grave and a carriage for travelling on the trackway said carriage having its wheels encircled in a suitable housing, the lower end of which projects down past each side of the tracks and to a point below the lower edge of the wheels, thereby concealing the wheels from view and at the same time providing suitable safety guides which will prevent the wheels from leaving the tracks. By providing housings with wheels therein beneath the carriage with the lower surfaces thereof disposed below the lowermost edges of the wheels, it is possible to use the lowering device in the conventional stationary manner and eliminate the trackway should the conditions be such as to demand it.

It is a further object of this invention to provide a burial apparatus comprising a trackway for carrying a casket carriage, said trackway comprising a pair of rails which are adjustably mounted relative to each other on suitable cross ties in order to make the same conform to different carriage gauges and different widths of graves.

It is a still further object of this invention to provide a burial apparatus comprising a trackway having a casket carriage mounted thereon, with means disposed on said trackway for stopping said carriage in a position where the casket is adapted to be lowered into the grave and a second means, manually operated, for securing the carriage in this lowering position to prevent any rearward or forward movement thereof during the lowering operation.

Some of the objects of the invention having been stated, other objects will appear as the description proceeds when taken in connection with the accompanying drawings, in which—

Figure 1 is an isometric view of a burial apparatus set up near a grave;

Figure 2 is an elevation looking at the near side of Figure 1 but showing the grave and surrounding earth in section and also showing the carriage in the lowering position;

Figure 3 is a sectional view taken along the line 3—3 in Figure 1;

Figure 4 is a sectional plan view taken along the line 4—4 in Figure 3 showing the central portion of the trackway and also showing the latching means for holding the carriage in position when it has been moved to lowering position;

Figure 5 is a sectional detail view taken along the line 5—5 in Figure 4;

Figure 6 is a sectional view taken along the line 6—6 in Figure 4;

Figure 7 is an isometric view of one of the adjustable rail shoes which is slidably mounted in suitable cross ties and supports rails which are placed thereon;

Figure 8 is a sectional view through the grave showing the lowering device in use where it is impossible to use the trackway.

Referring more specifically to the drawings the numeral 10 denotes a suitable pit into which the burial casket is lowered, said pit having placed at each end thereof suitable ties 11 for supporting rails 12 and 13. Each of the ties 11 are U-shaped in cross section and have their upper ends partially enclosed by inturned flanges 11a and 11b. Suitable shoes 15 are slidably mounted in these cross ties, said shoes having longitudinal grooves 17 and 18 in the side portions thereof into which the inturned portions 11a and 11b respectively are adapted to fit. A set screw 19 is threadably secured in the upper side of the shoe 15, the lower end of said screw being adapted to engage the top side of flange 11b when it is desired to fix the shoe in position. This shoe has a transverse slot 55

20 therein into which tracks 12 or 13 are adapted to fit.

In order to hold the rails in position after they have been inserted into the slots and also to prevent any relative movement longitudinally of the trackway between the rails and the shoe, a suitable pin 22 has been inserted in the shoes 15 at a point slightly above bottom of slot 20. The tracks 12 and 13 have notches in their lower sides 10 which are adapted to fit over the pins 22 (Figure 6) to hold the parts in position. It is also necessary to prevent the rails 12 and 13 from becoming separated; therefore the ends of these rails have been notched thereby forming interlocking 15 notched portions 12a and 13b on rails 12 and 13 respectively.

When the rails are mounted in its desired position a suitable carriage 25 is placed thereon. This carriage is adjustable both as to width and as to 20 length in order to accommodate different sizes of graves, and it comprises adjustable side members 26 and adjustable end members 27 which members are joined together by corner posts 28. Secured to the lower surface of each corner post 28 25 by any suitable means such as screws or bolts 29 is a housing 30, said housing having rotatably mounted therein flanged wheels 31 which are adapted to travel upon tracks 12 and 13. It will be noted that the lower surface of each housing 30 30 is flat and extends down a substantial distance below the lower edge of pulley 31. In order to allow the pulley to properly engage the tracks a suitable slot 33 has been cut in opposed sides of the housing 30 and these slots fall astride of 35 the track and form additional guiding means for preventing the carriage from running off of the track. This method of construction also provides a housing which conceals the wheels from view and thereby adds to the smoothness and general 40 appearance of the ceremony.

A casket 34 is placed upon the usual lowering straps 35 when the carriage is in the position shown in Figure 1. Thereafter the carriage is moved longitudinally of the trackways to the position shown in Figure 2 after which it is lowered 45 into the grave pit 10.

In order to insure that the carriage will be stopped at the proper position for lowering, suitable stops 36 have been adjustably secured to the 50 rails 12 by any suitable means such as set screws 37. These stops are adjusted in position prior to the ceremony. When the housings 30 engage these stops, then the casket 34 will be in the proper position for lowering. It is desirable then 55 to secure the carriage against any backward movement during the lowering operation; therefore a latch 38 has been provided which comprises a bracket 39 adjustably secured to rail 12 by any suitable means such as set screw 40. The 60 bracket 39 has pivotally secured in one end thereof a pin 41, the ends of said pin having prongs 42 and 43 secured thereon. The prongs 42 and 43 are

normally in the position shown in Figures 1, 4 and 5, but when the carriage has moved to a position where the foremost housings 30 engage the stops 36, then the trailing housings 30 will be disposed on the trackway 12 with their center line 5 midway between the prongs 42 and 43. At this time the latch 38 is tripped to the dotted line position as shown in Figure 5 which will prevent the housing from moving in either direction upon the trackway. 10

The prongs 42 and 43 of the latch 38 are actuated by a suitable spring 44 which spring has one end thereof secured to the bracket 39 and the other end to prongs 42. When the prongs are in the bold line position as shown in Figure 5, the 15 line of force exerted by said spring falls below the pivot 41 and therefore holds the latch against the lower side of the stop 39a, which is integral with bracket 37.

When the latch 38 is pulled upwardly by the 20 undertaker's foot during the burial ceremony to a point where the line of force falls above the pin 41, then the prongs 42 and 43 will be drawn to the dotted line position in Figure 5 where the prongs will be disposed on opposed sides of housing 30 to lock the carriage in position. It is therefore seen that this latch may be easily operated without the necessity of the director stooping to operate the same. In order to enable the latch members 42 and 43 to be removed from the path 30 of the wheels without the attendant stooping over, a projection 43a is provided which may be pressed by the foot of the attendant. 25

In the drawings and specification there has been set forth a preferred embodiment of the 35 invention, and although specific terms are employed, they are used in a generic and descriptive sense only, and not for purposes of limitation, the scope of the invention being set forth in the appended claim. 40

I claim:

An attachment for the legs of a burial apparatus lowering mechanism wherein the lowering mechanism comprises a carriage having four legs, the lower ends of which are provided with grooved 45 rollers for engagement with a trackway, said attachment comprising a base member having an enlarged upper surface serving to contact and support the lower ends of the legs of a burial apparatus, said attachment also having a broad 50 lower flat surface provided with a groove bisecting said lower surface, a grooved roller mounted in said groove, the lowermost portion of the roller being disposed above the plane defined by the 55 lower surface of said attachment, whereby the groove in said lower surface will act as a guide for the roller when the lowering mechanism is disposed on a trackway, and the broad lower surface will hold the roller out of contact with the ground when the lowering mechanism is not disposed on a trackway. 60
